UNITED STATES PATENT OFFICE.

CHARLES ASHTON HENRY BULLOCK, OF LONDON, ENGLAND.

TYPESETTING APPLIANCE.

Application filed May 2, 1921. Serial No. 466,030.

To all whom it may concern:

Be it known that I, CHARLES ASHTON HENRY BULLOCK, a subject of the King of Great Britain, and resident of London, England, have invented certain new and useful Improvements in Typesetting Appliances, of which the following is a specification.

This invention relates to type setting appliances and has for its object to provide a more convenient and effective means whereby type can be set.

The method of setting type by hand at present generally in use is to store the separate type in boxes or cases from which they are extracted.

The invention consists broadly in providing channels to contain the type so disposed that the types tend to gravitate from the top to the bottom of the channel, means being provided whereby the lowermost type in each channel is caused to assume a convenient and ready position for extraction.

According to the preferred form of my invention I store the type in channels so disposed that the type tends to gravitate from the top of the channel to the bottom, the channels being pivoted at their upper ends and having at their lower ends means whereby the depression of the channel as a whole will cause the first type to be raised or elevated in position convenient for extraction.

I may, however, use fixed channels and provide a movable device in connection with each for elevating the first type into position convenient for extracting. Each device may comprise a key, spring controlled or otherwise, the depression of which is adapted to cause a sliding member at the end of the channel to raise the first type into position convenient for extraction. I use a bridge piece or equivalent device providing a suitable slot or hole so as to prevent raising of more than one type at a time.

In carrying the invention into practice according to one embodiment I provide a number of channels disposed side by side, each channel being a separate container which may conveniently be formed of stamped or bent metal. Each of these channels is filled with its particular designation of type, letter or symbol, and the channels are disposed at a sufficient angle to ensure the type falling by gravity to the bottom end of the sloping channels. Each of the channel structures is pivoted at its upper end and at its

lower end is provided with a finger piece which may conveniently take the form of a disc having a hole or slot coincident and immediately above the lowest type in the channel, so arranged that pressure applied to the disc will ensure the elevation of a single type.

In order that the invention may be clearly understood and readily carried into practice I will now describe the same more fully by reference to the accompanying drawings in which:—

Fig. 1 is an end elevation of a type setting appliance embodying my invention.

Fig. 2 is a front elevation looking in the direction of arrow A (Fig. 1).

Fig. 3 is a detail showing one of the type channels detached.

Fig. 3^a an end view of Fig. 3.

Fig. 4 a detail of the distributing channel hereinafter more fully referred to, and

Fig. 5 a portion of the chase or form used in conjunction with my appliance.

Figure 6 is a section through one of the type channels.

Referring to the drawings the numeral 1 represents the frame of the machine supported at a suitable angle by legs 2 pivotally mounted at their upper ends 2^a to the frame 1. 3 represents the channels containing the type. These channels are disposed side by side extending across the machine, and arranged in rows as shown in Fig. 2, and disposed at a suitable angle so that ready access is given to each channel for the purpose of extracting the piece of type therefrom, and, to ensure the type falling by gravity to the bottom end of the sloping channel. This action may be assisted and friction diminished by shaping the bottom of such channel to give a convex or inverted V section as indicated by Fig. 6.

Each of these channels 3 is filled with its particular designation of type letter or symbol, and each is pivotally mounted at its upper end 3^a on a rod 4 carried by a bracket 5 secured to the frame. At the lower ends of the channels 1 provide a finger piece 3^b which may conveniently take the form of a disc and may have a hole or slot coincident and immediately above the lowest type in the channel. Or the disc 3^b may be disposed as shown slightly above the lower end of the channel leaving sufficient space for the extraction of a single piece of type. The finger pieces or discs are preferably hinged so that they may be lifted up out of the way

if desired. Light springs 6 or other means are provided to constrain the channels to adopt positions with their lower ends slightly elevated in respect of stationary stops or 5 projections 7 disposed beneath their extremities. These stops 7 may conveniently be formed on bars 8 extending across the machine and are adapted to register with slots 3^c in the channels so that on depression of a 10 channel or channels these stops 7 come into contact with and support the last piece of type which thus remains stationary whilst the other pieces of type in the channel are carried down with the channel. The channels 15 thus operate like a series of keys and on depression of the key or channel in which the desired letter is stored, this operation causes the first or lowermost type of the series to project through the space or opening provided to a position between the finger and thumb and the type may thus be readily extracted for removal to the printer's stick or chase. In order to prevent more than one 20 type piece being extracted at a time the hole or space in or below the disc 3^b is so proportioned so to allow the passage only of the lowest type. On release of the key or channel the same is automatically returned to its correct position by means of the spring 6. 25 A stop or projection 3^d on the channel engaging the underside of the fixed stop 7 thus limits the upward movement of the channel. Instead of a separate spring for each channel or key I may, if desired, have one 30 common spring for each row of keys, each row being interconnected in such a manner that on depression of any one key the whole row is automatically depressed and the lower most type in each channel of the series raised 35 to a position convenient for extraction. The upper parts of the bars 8 may be formed as shown at 8^a to act as a guide when a key is depressed.

For the purpose of easy distribution of 40 the type from the chase the upper portion of which is shown in Fig. 5 I provide a distributing channel 12 as shown in Fig. 4 which is detachably mounted upon the frame 1 of the appliance. When distributing the 45 type a thumb nut 9 on the chase (Fig. 5) is released to enable a sliding bar 10 to be slid down a short distance to create a gap or space at the end of the row of type; a bolt 9^a working in a slot 11^a in a fixed block 11. 50 The distributing channel has a pin 12^a therein which is adapted to fit within a hole in the chase and the row of type may then be transferred to the distributing channel. The channel is now released from the chase and 55 its pin 12^a placed within a hole on the pivotally mounted spring controlled tumbling block 13 on the typesetting appliance and supported by a pin 14 thereon. For distributing the type from the channel the said 60 channel 12 is depressed and a fixed pin or 65

projection 14^a on a pivotally mounted guide 15 engages the lowermost type to raise the same into a position convenient for extraction as heretofore described with reference to the channels 3. 70

Furthermore it is desirable when distributing to have all the channels 3 in alignment or with their upper surfaces flush and in one plane and not projecting intermittently and alternately, row for row, one above the other as preferably is the case when setting the type and as shown in Fig. 1. For this purpose I provide a lever 16 at each end of the appliance pivotally mounted at 16^a to a bracket on the frame. 75 To these levers the lower ends 8^c of the bars 8 are mounted, the bar in communication with the lower row of keys being fixed to the plates 1^a on the appliance since it is unnecessary that this bar should move. A 80 hinge 17 is secured to the frame and an operating handle 18 is mounted upon the free end of said hinge. It will be readily understood on reference to Fig. 1 that when the handle 18 is operated the levers 16 are 85 moved to the position shown in dotted lines thus bringing all the rows of keys flush or level and to a position whence it will be easier to place the distributed type in the respective channels. The bars 8 in this 90 movement are guided in slots in the plates 1^a, and stop plates 8^b engaging the underside of the plates 1^a are provided for limiting the upward movement of the said bars 8. It may be found preferable in practice 95 with a view to avoiding any disturbance of the types as a consequence of a too rapid or jerky movement to replace the lever movement by a screw of suitable pitch. 100

Extension channels 19 may be provided 105 when desired for accommodating more type than one of the channels 3 will take.

The discs 3^b may have a symbol or indication thereon indicating the character or type in the channel. 110

In order to ensure that the type in the channels does not assume a slanting position with the bottom of the type in the rear, I may provide a rod, pin brush or the like to stroke or rub the bottom of the 115 type in the direction in which they are travelling. This may be provided for by having a slot in the bottom of the channel through which a rod pin or brush or the like works. 120

Instead of the stationary stop hereinbefore referred to the stops may be carried by the channels so that when each channel is depressed the stop itself is raised by contact with the base or bedplate, or I may employ stationary channels and separate keys. By depressing any desired key I may operate a rack or lever mechanism to raise the stop in the corresponding channel and thereby lift the lower type. 125 130

What I claim and desire to secure by Letters-Patent is:

1. A type setting appliance comprising a frame, means for supporting said frame at an angle to the horizontal, a plurality of channels adapted to contain type, arranged side by side within said frame, a common rod upon which all said channels are pivoted, spiral springs connected between said rod and said channels for biasing said channels to elevated position, stops for limiting the upward movement of said channels, finger pieces at the lower ends of said channels, openings adjacent said finger pieces, a fixed stop beneath each channel adapted to pass into its appropriate channel when said channel is depressed by the finger piece, said stop operating against the foot of a single type to insure its being extended through the opening adjacent the finger to a position where it can be readily withdrawn by the operator, substantially as specified.
2. A type setting appliance comprising

a frame, means for supporting said frame at an angle to the horizontal, a plurality of channels adapted to contain type, arranged side by side within said frame, a common rod upon which all said channels are pivoted, spiral springs connected between said rod and said channels for biasing said channels to elevated position, stops for limiting the upward movement of said channels, finger pieces at the lower ends of said channels, openings adjacent said finger pieces, a fixed stop beneath each channel adapted to pass into its appropriate channel when said channel is depressed by the finger piece, said stop operating against the foot of a single type to insure its being extended through the opening adjacent the finger piece to a position where it can be readily withdrawn by the operator, means for actuating all said channels to bring them all into alinement so that they lie flush and in the same plane, for facilitating distribution substantially as specified.

In witness whereof I affix my signature.

CHARLES ASHTON HENRY BULLOCK.
